Fig. 2.

Technical cross-sectional diagram of a mechanical device, showing a complex assembly with various parts labeled with numbers and letters. Key components include a central vertical cylinder (14), a piston (40), a rod (36), a valve assembly (60, 30), and a base structure (A, B, C, D, E, F). Various parts are labeled with numbers such as 3, 17, 41, 81, 83, 79, 79a, 79c, 70, 15, 11, 66, 67, 71, 65, 72, 61, 31, 78, 12, 79, 10, 12a, 79, 67, 13, and 31. The diagram is highly detailed, showing internal mechanisms and external structural elements.

UNITED STATES PATENT OFFICE.

FRANK B. H. GARSON, OF LAWRENCE, MASSACHUSETTS.

INTERNAL-COMBUSTION ENGINE.

Application filed June 8, 1923. Serial No. 644,198.

To all whom it may concern:

Be it known that I, FRANK B. H. GARSON, a citizen of the United States, residing at Lawrence, in the county of Essex and State 5 of Massachusetts, have invented certain new and useful Improvements in Internal-Combustion Engines, of which the following is a specification.

This invention relates to improvements 10 in internal combustion engines.

The primary object of this invention is the provision of an internal combustion engine in which the expansion and explosive qualities of a fuel used therein are utilized 15 to the maximum extent for power generation.

A further object of this invention is the provision of a novel type of rotary valve control for the intake and exhaust of fuel 20 charges of internal combustion engines.

A further object of this invention is the provision of means for utilizing exhaust gases after their escape from the internal combustion engine cylinder chambers, conveying 25 them to a turbine operatively connected to the internal combustion engine crank shaft where their complete forces may be used in the generation of power.

Other objects and advantages of this invention will be apparent during the course 30 of the following detailed description.

In the accompanying drawings, forming a part of this specification, and wherein similar reference characters designate corresponding parts throughout the several 35 views.

Figure 1 is an end elevation of an internal combustion engine constructed in accordance with features of this invention.

40 Figure 2 is a fragmentary view, partly in section, and partly in side elevation, showing improved features of this invention.

Figure 3 is a transverse cross sectional view, taken through the internal combustion engine substantially on the line 3—3 of Figure 2.

45 Figures 4 and 5 are views showing the construction of a rotary valve employed in the internal combustion engine for the control of fuel intake and exhaust gases.

Figure 6 is a fragmentary view, illustrating a valve seating surface, showing more particularly the means for feeding lubricant to the valve.

55 In the drawings, wherein for the purpose of illustration is shown the preferred em-

bodiment of this invention, the letter A may generally designate the internal combustion engine, which may include a housing construction B; crank shaft C, piston means D for operating the crank shaft C; a turbine E connected to the crank shaft C; rotary valve means F for control of intake and exhaust gases, and means G for drive of the valve F by the crank shaft C.

60 Referring to the housing B, the same may include a sectional crank case 10, including as parts thereof upper and lower crank case portions 11 and 12^a, which embody novel casings 12 for the accommodation of the turbines E to be subsequently described. The cylinder block 14 is provided as a part 65 of the housing B, within which the cylinder chambers 15 are formed in any desired number according to the type of engine desired.

A detachable cylinder head 16 is also provided, in the top whereof the detachable spark plugs 17 may fit. It is preferred that the engine A be of the water cooled type, and to this end water compartments 20 are 70 provided about the cylinder chambers 15 as in ordinary construction. For each cylinder 75 of the internal combustion engine, intake and exhaust ports 25 and 26 respectively are provided in the cylinder blocks 80 or heads 14 and 16, to one side of the internal combustion engine; said intake and exhaust ports or passageways communicating with the rotary valve means F to be subsequently described. Between the intake and 85 exhaust ports 25 and 26 of each cylinder chamber, the water passage 27 is provided.

The crank shaft C is of any approved type, and is preferably supported intermediate sections 11 and 12^a of the crank case 10. 90 The piston means D may include the ordinary pistons 30 operating within the cylinder 95 15, and connected with the throws of the crank shaft as by means of the connecting rods 31.

100 Referring to the construction of the internal combustion engine housing B, for the accommodation of the rotary valve control, it is preferred to provide a complete rotary valve 35 for each cylinder of the internal combustion engine; said rotary valves being mounted upon a shaft 36, which extends longitudinally of the motor and is operated from the crank shaft C by means of the transmission G to be subsequently 105 described. The cylinder block 14 of the housing B is preferably provided with a

semi-circular valve seat 37 for each cylinder chamber, at the side of the housing B upon which the intake and exhaust ports are provided. A valve block 40 is provided as a part of the housing B, which is for detachable connection to the cylinder block 14 and cylinder head 16, as by bolts 41, to effectively seat the valves 35. The block 40 is provided with a semi-circular valve 10 seat 42, for each rotary valve 35, which when the block 40 is placed upon the housing B cooperates with the valve seat 37 in receiving a valve 35 for rotation therein. The valve block 40 is preferably provided 15 with ports 44 and 45 which communicate respectively with the intake and exhaust ports 25 and 26 above mentioned, and which, of course, lead to the rotary valve 35 for control of fuel intake and exhaust. An 20 intake manifold 47 is preferably detachably carried by the valve block 40, having ports 48 which communicate the same with the rotary valve 35, for the intake of fuel to the engine cylinders, as will be subsequently 25 described. The cylinder blocks 14 for each rotary valve is provided with a passageway 49 which leads from the valve seat 37 downward and which is provided for leading the exhaust gases direct from the cylinders 30 to the turbines E, as will be subsequently described in detail.

It is preferred to provide means for lubricating the rotary valves 35 when within their seats in the housing B. To this end, an oil 35 reservoir 52 is preferably provided in the block 40, between the intake and exhaust passageways thereof, and which is provided with outlet ports 54 and 55, for each rotary valve; said outlet ports 54 and 55 leading 40 directly out to the valve seats 42 provided in the block 40 for each valve 35. An oil line 57 is preferably provided, through which oil may be pumped to the reservoirs 52. It is preferred to provide diverging 45 grooves 59, substantially in X-shaped relation, for each of the oil outlets 54 and 55; said grooves of course intersecting said outlet openings so that oil may be more uniformly and evenly distributed over the valve 50 rotating thereover.

Referring to the means for utilizing the gases after exhaust from the engine cylinders, so that the same may be used to fullest extent for power generation, it is preferred to place a turbine E substantially at the division line of each pair of cylinders in the internal combustion engine A, so that the same may receive the exhaust from two cylinders for operation. The turbine E is preferably of a type providing concavo-convex blades 60 at the outer periphery thereon. Each of the turbines E are placed upon a bearing portion 61 of the crank shaft C, as by being keyed thereto, said bearing portion 61 preferably being journalled

in the turbine casing 12 above mentioned. The turbine casing 12 may be formed as a part of the crank case 10, and as it is preferred to provide turbines of relatively great diameter, the casing 12 therefor may 70 extend beyond the outer surfaces of the ordinary crank case, substantially as is illustrated in the drawings. Each of the turbine case portions 12 is preferably provided with a tangential inlet opening 63 into which a pipe connection 64 extends, said pipe connection 64 at its upper end being flanged for detachable connection to the cylinder block 14, as to provide a continuous passageway for the flow of exhaust gases into the inlet opening 63 of the turbine case 12, so that the exhaust gases may impinge tangentially upon the turbine blades 60. At the opposite side of each turbine case 12, an exhaust passageway 65^a may be provided, which may be in the form of an exhaust manifold, if desired, and through which the dissipated gases may escape from the turbine casing, after complete expansion and combustion. Each of the turbine casings 12 is preferably constructed as to provide air passageways 65 at each side of the turbine E revolving therein, said passageway 65 preferably having atmospheric communication and any approved means for directing a current of air therethrough. As throws 66 of the crank shaft C are disposed at each side of the turbine casing 12, it is preferred that splash plates 67 be located upon the bearing ends of the connecting rods 31 about said throws 66; said splash plate 67, of course, inclining with respect to the plane in which the turbine casing 12 is disposed, so that the same may splash lubricant from the oil compartment 70 in the crank case 10, against the sides of the turbine casing 12. A plurality of radially disposed oil cups 71 are preferably provided at each side of the casing 12, having oil 100 passageways 72 therein, which are open at the tops of the oil cups, and which lead to the bearings of the crank case in which the portion 61 of the crank shaft are journalled. The openings of the oil cups 71 are 105 arranged at different elevations about the crank case 12, on each side thereof substantially as is illustrated in Figure 3 of the drawings, so that the crank shaft may be properly lubricated in its bearings by continuous supply of oil. It is preferred that ducts 78 be provided in the turbine case 12 at each side thereof, below the bearing portions 61 of the crank shaft and through which lubricant may flow and exit thru 110 openings 79 adjacent the bottom of the crank case. 115

Referring to the drive of the rotary valve 35 by means of the transmission mechanism G, it is preferred to provide a shaft 78 at 120 an end of the internal combustion engine A, 130

rotatably supported, as by brackets 79, and at its lower end preferably being connected for rotation with the crank shaft C, as by miter gears 80, which, of course, are of the same size. At its upper end, the shaft 78 is connected to the rotary valve shaft 36, for drive of the latter as by means of bevelled gears 83 and 84 respectively connected to the shafts 78 and 36; the former gear preferably being the smaller, and with a ratio of two to one. This means of gear connection need not be adhered to, as it is only necessary that the rotary valve revolve once to two revolutions of the crank shaft case to 15 provide for the correct timing of intake and exhaust.

Referring to the construction of a rotary valve 35, it is preferred to make each of the same of sectional construction, each rotary valve including sections 85 and 86, which are provided with the outer convex surfaces 87. It is preferred that the sections 85 be provided with a keyway therein, by means of which the same may be keyed, as at 90, to the rotary valve shaft 36; the abutting faces of the sections 85 and 86 being transversely grooved to receive the rotary valve shaft 36. Inwardly of the convex surface 87 of the section 86, it is preferred to provide the control port 92, the surface of which is arcuate and which is of sufficient capacity to permit the proper intake and exhaust of fuel gases, as will be hereinafter described. Screws 94 are preferably provided for connection of the sections 85 and 86; being inserted from the port 92, so that the convexity 87 of the valve 35 is not obstructed by projections or depressions of any sort. When the sections 85 and 86 are assembled, 40 they provide the flat sides 97 which abut certain flat surfaces of the housing which receives the same.

Referring to the operation of the internal combustion engine A, the vaporized fuel is fed from the carburetor through the intake manifold 47, and thence through the passageway 48 to the rotary valves 35. The rotary valves 35 are preferably rotated clockwise, and the fuel charge is fed from the intake manifold to the internal combustion engine cylinders by way of the rotary valve ports or kerfs 92, as can readily be understood from the illustration of Figure 3 of the drawings. The exhaust of the gases after the power stroke is through the housing port 26, and by way of the rotary valve port 92 into the turbine passageway 49. The rush of exhaust gases incident to the up-stroke of the pistons 30, and also incident to the expansion of the gases which has not been fully effected during the power stroke, 55 propel the exhaust of the gases with considerable force against the blades of the turbine E. This rush of exhaust gases incident to engine action, expansion of gases, and

further explosion of the same, produces a considerable force, which in the ordinary internal combustion engine is entirely lost, in so far as any power generation is concerned. In the improved type of internal combustion engine A, such force of the exhausting gases and fuel is directly taken by the turbine E, for the increase in efficiency of power generation, as can well be understood. The discharge of the completely exhausted gases is through the outlet 65 as above mentioned. With this type of internal combustion engine, it is apparent that the provision of the rotary valves 35 does away with the complicated poppet valve and cam shaft operating mechanism ordinarily provided upon conventional internal combustion engines. The rotary valve, it is to be observed, not only cooperates in the intake and exhaust of gases with respect to the internal combustion engine cylinders, but cooperates in properly directing the exhaust gases through the turbine E for increased efficiency of engine operation. The provision of the turbine E also obviates the necessity of providing mufflers, as the sound is completely muffled after travel about the turbine E. It is to be observed that the turbines E are of considerable mass, which obviates the necessity of providing a fly wheel.

Various changes in the shape, size and arrangement of parts may be made to the form of invention herein shown and described, without departing from the spirit of the invention or the scope of the claims; but,

I claim:

1. In an internal combustion engine, a casing including a cylinder chamber and a cylindrical valve chamber at one side of the cylinder chamber, said valve chamber having an inlet and an outlet spaced circumferentially of the valve chamber, the cylinder chamber having intake and exhaust ports communicating with the valve chamber between the inlet and outlet and in spaced relation circumferentially of the valve chamber, a rotary valve member in said valve chamber having a circumferentially disposed peripheral pocket for controlling communication between the ports and inlet and outlet during rotation of the valve, a piston operating in said cylinder, a crank shaft connected with said piston, and means for imparting rotary movement to the valve in timed relation to movement of the piston.

2. In an internal combustion engine, a casing including a crank case, a cylinder chamber and a cylindrical valve chamber at one side of the cylinder and having an inlet and an outlet spaced circumferentially of the valve chamber and inlet and exhaust ports disposed one above the other and lead-

- ing from the cylinder chamber and communicating with the valve chamber between the inlet and outlet, the casing between said intake and exhaust ports being provided with
5 an oil pocket having an outlet communicating with the valve chamber, a piston operating in said cylinder chamber, a rotary valve in said valve chamber for controlling communication of the inlet and exhaust
10 ports with the inlet and outlet of the valve chamber, and means for rotating the valve in timed relation to movement of the piston.
3. In an internal combustion engine, a
15 casing including a crank case, a cylinder block, a cylinder head, and a valve block mounted at one side of the cylinder head; said cylinder head provided with intake and exhaust ports disposed one above the other, said cylinder block and valve block having
20 registering arcuate recesses providing a cylindrical valve chamber and having cir-

cumferentially spaced inlet and outlet passages for live and burnt gases and passages leading from the valve chamber between the inlet and outlet passages and communicating with the intake and exhaust ports of the cylinder head, the valve block between the passages leading to the intake and exhaust being provided with an oil reservoir pocket having outlet openings communicating with the valve seat and having an inlet for receiving a feed pipe, a crank shaft in said crank case, a piston in said cylinder block and connected with the crank shaft, a rotary valve in the valve chamber, and means for imparting movement from the crank shaft to the rotary valve whereby said valve may be operated in timed relation to movement of the piston and control passage of gases through the passages leading from the 40 valve chamber.

FRANK B. H. GARSON.
